SHIRT PACKAGING DEVICE

William W. McFall, River Forest, Ill.

Application November 9, 1945, Serial No. 627,698

9 Claims. (Cl. 223—71)

1

This invention pertain to improvements in a shirt packaging device of the type employed by laundry establishments.

It is an object of the invention to provide a novel shirt packaging device adapted to enclose and protect the collar of a man's collar-attached shirt in a sturdy manner resistant to crushing pressures applied during handling.

A still further object is to provide a packaging device including a shirt reinforcing base or backing panel and a collar protective panel spaced vertically above the backing panel to overlie the shirt collar, in association with a separate collar bracing form operatively connected to the collar protecting panel in a manner to unite the two parts of the device into a rigid protective unit safeguarding the collar from crushing, and in addition enabling a plurality of thus packaged shirts to be stacked in staggered order for quick and easy wrapping into a package which is strongly reinforced at its ends against damage from mishandling.

The foregoing statements are indicative in a general way of the nature of the invention, but other and more specific objects will be apparent to those skilled in the art upon a full understanding of the construction and operation of the device.

One embodiment of the invention is presented herein for the purpose of exemplification, but it will be appreciated that the invention is susceptible of incorporation in other modified forms coming equally within the scope of the appended claims.

In the drawings,

Fig. 1 is a diagrammatic view in longitudinal section illustrating a shirt positioned on a well known type of packaging table for a folding operation, during which the device of my invention is initially associated with the shirt;

Fig. 2 is a plan view illustrating the backing sheet constituting a part of the packaging unit of the invention;

Fig. 2-a is a plan view illustrating the collar supporting and locking element of the packaging unit;

Fig. 3 is a fragmentary plan view, illustrating one element of the packaging device or unit in final operative position, the remaining element having been arbitrarily omitted for clarity of showing;

Fig. 4 is a fragmentary perspective view illustrating the unit partially applied to the shirt; and

Fig. 5 is a fragmentary plan view illustrating the parts of the unit following final folding from the position of Fig. 4.

Referring to the drawings, in Fig. 1 I conventionally illustrate a well known type of shirt wrapping bench or table, such as is in common use in laundry establishments for the folding of men's

2

shirts. This comprises a flat table surface 10 having a depression or well 11 therein adapted to receive the neckband or collar of the shirt, which is generally designated 12. The table has pivoted thereto an elongated rectangular metal form 13 of aluminum or the like, and in the normal use of a folding device the shirt is positioned face downward on the table surface 10 with the collar thereof extending downwardly into the well 11, after which the form 13 is hingedly depressed onto the shirt. The sides of the shirt body and sleeves are then folded upwardly and inwardly onto the form and held in this assembled relation by pins and/or a paper wrapper initially disposed on the table beneath the shirt. In case a stiffening or backing sheet is to be applied to the shirt prior to folding of the body and sleeves as described, this sheet is initially disposed in a hook-shaped element or elements 14 on the under surface of the form 13, to be lowered onto the shirt coincidentally with the pivoting of said form. This type of equipment is widely employed in laundries, and will be normally availed of in the first step of assembly of the wrapping device of this invention with a shirt.

Referring to Figs. 2 and 2-a, wherein I illustrate the component parts of the device, the reference numeral 15 designates a rectangular sheet member of a suitable grade of paper board which is transversely creased or scored along parallel lines 16, 17 to subdivide the same into a rectangular base or backing panel 18, a rear wall 19 and a top collar-protecting panel 20. It will be understood that the member 15 is fabricated using a suitable die, which additionally has provision to form a generally triangular opening 21 in the panel 20. A pair of foldable tabs 22 are disposed adjacent the two rearmost sides of this triangular opening in the flat condition of sheet 15, being hinged to the panel 20 on short creased fold lines 23 and separated therefrom by pairs of slits 24, 24 and 25, 25. The tabs 22 are separated from one another by the further slit 26 between the midpoint of the pair of slits 25, 25, and the apex of the triangular opening 21. In use, these tabs are intended to be folded downwardly at right angles to the plane of the panel 20.

The second element of the device is illustrated in Fig. 2-a being designated generally by the reference numeral 27. This functions as a collar supporting element for the shirt and also as a lock releasably holding the two components of the device in operative position. The element 27 is stamped from paper board similar to the sheet 15 to provide a collar brace portion 27' having a pair of curved, laterally extending wings 28, a spaced locking and supporting or strut portion 29, also having laterally extending supporting wings 30, and a central connecting portion 31 extending between the collar brace 27'

at the juncture of wings 28 and the further portion 29, being bendably connected to the brace and strut portions by creased foldlines 30', 30" respectively. This connecting portion 31 is of substantial dimension transversely of the length of the wings 28, 30, so as to afford a substantial ledge locating the portion 29 well to the rear of the collar bracing wings 28 in the operative assembled condition of the device, to be described.

In use, the sheet 15 is positioned on the swingable form 13, with the panel 20 engaged in the hook member or members 14 thereon. With a shirt disposed on table 10 in the manner illustrated in Fig. 1, the form and sheet are swung downwardly, and the shirt body and sleeves wrapped therearound and secured in the conventional fashion. The form 13 and encasing shirt are then swung upwardly and the shirt and sheet slipped longitudinally off the metal form 13. The sheet 15 is then slid longitudinally outwardly past the collar of the shirt until the inner fold line 16 is approximately coincident with the rear portion of the shirt neckband 12.

Next, the end panel 20 and rear wall 19 are folded upwardly on the fold line 16 and the panel 20 is then folded forwardly on line 17 placing the same parallel to backing panel 18 over the top of the shirt collar. With the parts in this condition, or immediately prior to the folding of the panel 20 and rear wall 19, the second element 27 is associated with the collar by slipping the wings 28 thereof underneath the collar, between the same and the shirt neckband. Then, with the panel 20 overlying the shirt collar, in the position of the parts illustrated in Fig. 4, the element 27 is folded first on line 30' to bring the connecting portion 31 over the end of the panel 20, then downwardly on line 30" to bring the portion 29 thereof into the triangular opening 21. This simultaneously swings the tabs 22 downwardly around their fold lines 23 into a vertical position, likewise bending the wings 30 of the portion 29 inwardly to an arcuate form, as said wings brush downwardly past tabs 22. Fig. 3 illustrates the final position of the tabs 22, the locking element 27 having been omitted entirely from this view for clarity of illustration.

Upon completion of the last mentioned operation, the wings 30 will pass underneath the side margins of the opening in panel 20 immediately adjacent the slits 24, and, by their inherent resiliency, snap outwardly underneath the panel at that point to lock the parts against inadvertent displacement, finally reaching a position behind or inwardly of and generally parallel to the downturned tabs 22. In this final position, illustrated in Fig. 5, the wings 30 extend vertically in the manner of struts between the lower side of the panel 20 and the back of the shirt, braced by the backing sheet 18. Due to this rigid support by wings 30, in conjunction with the vertical support afforded by the rear wall 19, the collar is effectively protected against vertical crushing loads. The locking tabs 22 may or may not be of sufficient vertical extent in folded condition to engage the shirt similarly, so as to further this support.

The forward collar bracing wings 28 serve to sustain the collar effectively, providing a still further measure of vertical support between the collar itself and the neckband. At least a double-ply thickness of paper board is disposed vertically adjacent the forward portion of the collar neckband, to act as a vertical strut at that point the wings 30 being spaced rearwardly from the neck-

band by the depending tabs 22. Needless to say, the collar is well shielded from soilage.

This completes the operations attending the application of the device to a shirt resulting in a package having a rectangular end. A plurality of shirt packages of this type may be assembled in complementary end for end reversed and staggered, stacked relation to provide a pile having rectangular ends which lends itself admirably to wrapping in an outer wrapping sheet. This results in a built-up package which is comparatively rigid at its ends and thereby resistant to crushing or distortion, and which is well adapted for stacked display or storage on shelves and for stacking for delivery.

I claim:

1. In a shirt packaging device, a generally rectangular sheet member of flexible fibrous material adapted to be subdivided along parallel lines of fold into a backing panel adapted to be positioned adjacent the back of a shirt, a rear wall and a collar protecting panel, and a collar supporting and locking member insertable between the collar and neckband of the shirt having a pair of bracing wings, said rear wall and panel being foldable along said lines to bring the protecting panel into position over the collar in parallelism with the backing panel, said protecting panel having an opening therein and tabs hingedly connected to the margin of the opening to fold downwardly in said opening relative to said protecting panel, said supporting and locking member being positioned adjacent said protecting panel and forwardly of said opening therein when inserted between said collar and neckband, said bracing wings being swingable rearwardly relative to said protecting panel and downwardly through said opening and being flexible outwardly beneath said protecting panel to lock the members into retaining engagement therewith.

2. In a shirt packaging device, a generally rectangular sheet member of flexible fibrous material adapted to be subdivided along parallel lines of fold into a backing panel adapted to be positioned adjacent the back of a shirt, a rear wall and a collar protecting panel, and a collar supporting and locking member having collar sustaining wings insertable between the collar and neckband of the shirt and having a pair of bracing wings spaced from said collar sustaining wings, said rear wall and panel being foldable along said lines to bring the protecting panel into position over the collar in parallelism with the backing panel, said supporting and locking member being positioned adjacent said protecting panel and forwardly of said opening therein when inserted between said collar and neckband, said protecting panel having an opening therein and tabs hingedly connected to the margin of the opening to fold downwardly in said opening relative to said protecting panel, said supporting and locking member being positioned adjacent said protecting panel and forwardly of said opening when said sustaining wings are inserted between said collar and neckband, said bracing wings being swingable rearwardly relative to said protecting panel and downwardly through said opening and being flexible outwardly beneath said protecting panel to lock the members in operative relation into retaining engagement therewith.

3. In a shirt packaging device, a generally rectangular sheet member of flexible fibrous material adapted to be subdivided along parallel lines of fold into a backing panel adapted to be

positioned adjacent the back of a shirt, a rear wall and a collar protecting panel, and a collar supporting and locking member insertable between the collar and neckband of the shirt having a pair of bracing wings, said rear wall and panel being foldable along said lines to bring the protecting panel into position over the collar in parallelism with the backing panel, said protecting panel having an opening therein and tabs hingedly connected to the margin of the opening to fold downwardly in said opening relative to said protecting panel, said bracing wings being swingable rearwardly relative to said protecting panel and downwardly through said opening and being flexible outwardly beneath said protecting panel to lock the members in operative relation into retaining engagement therewith, said bracing wings being of adequate width to engage and sustain crushing load between said last named panel and backing panel.

4. In a shirt packaging device, a generally rectangular sheet member of flexible fibrous material adapted to be subdivided along parallel lines of fold into a backing panel adapted to be disposed against the back of a shirt, a rear wall and a collar protecting panel, and a locking member having means insertable between the collar and neckband of the shirt and a pair of divergent locking arms, said rear wall and panel being foldable along said lines to bring the panel over the collar parallel to the backing panel, said protecting panel having an opening therein, said locking member being positioned adjacent said protecting panel and forwardly of said opening, with said means inserted between said collar and neckband, and said locking arms being swingable rearwardly relative to said protecting panel and downwardly through said opening, said locking arms being adapted to flex outwardly beneath and into engagement with said protecting panel to lock the members in operative relation.

5. In a shirt packaging device, a generally rectangular sheet member of flexible fibrous material adapted to be subdivided along parallel lines of fold into a backing panel adapted to be disposed against the back of a shirt, a rear wall and a collar protecting panel, and a locking member having means insertable between the collar and neckband of the shirt and a pair of divergent locking arms, said rear wall and panel being foldable along said lines to bring the panel over the collar parallel to the backing panel, said protecting panel having an opening therein, said locking member being positioned adjacent said protecting panel and forwardly of said opening, with said means inserted between said collar and neckband, and said locking arms being swingable rearwardly relative to said protecting panel and downwardly through said opening, said locking arms being adapted to flex outwardly beneath and into engagement with said protecting panel to lock the members in operative relation, said arms being of sufficient width to engage said last named panel and transmit vertical load thereon to the backing panel.

6. In a shirt packaging device, a generally rectangular sheet member of flexible fibrous material subdivided by parallel fold lines into a backing panel, a rear wall and a collar protecting panel, and a collar supporting and locking member separate from said first named member,

including sustaining means insertable between the collar and neckband of the shirt and a pair of locking elements, said rear wall and panel being foldable along said lines to bring the protecting panel over the collar, said protecting panel having an opening therein and having tabs hingedly connected thereto to fold downwardly in said opening, said supporting and locking member being positioned adjacent said protecting panel and forwardly of said opening, with said sustaining means inserted between said collar and neckband, said locking elements being bendable rearwardly relative to said protecting panel and downwardly through said opening into operative position adjacent said tabs and having locking engagement with the sheet member in that position.

7. A shirt packaging device comprising a shirt engaging board including a panel positionable in overlying relation to the collar and neckband of a collar-attached shirt, said panel having an opening therein adapted to register with said neckband in said overlying relation, and an element predeterminedly positionable relative to a side of said opening and to the shirt neckband by engagement between the collar and neckband thereof, said element including a portion which is foldable over said neckband and into said opening and has locking engagement with said board in the thus folded condition thereof.

8. A shirt packaging device comprising a shirt engaging board including a panel positionable in overlying relation to the collar and neckband of a collar-attached shirt, said panel having an opening therein adapted to register with said neckband in said overlying relation and having elements bendably connected thereto at the margin of said opening which are positionable within and adjacent the shirt neckband, and an element predeterminedly positionable relative to a side of said opening and to the shirt neckband by engagement between the collar and neckband thereof, said last named element including a portion which is foldable over said neckband and into said opening to be adjacent said first named elements and has locking engagement with said board in the thus folded condition thereof.

9. A packaging device for a collar-attached shirt comprising a shirt board having a neckband covering and protecting panel which overlies the shirt neckband and is apertured in a zone overlying said shirt neckband when the board and panel are operatively positioned relative to a shirt, and a support separate from said board which is fixedly engageable with the shirt adjacent said panel and between the shirt collar and neckband, said support being foldable relative to said panel into the aperture in the latter into retaining engagement with the shirt board.
